SHIRT COLLAR SUPPORT

Filed June 21, 1948

FIG. 1

FIG. 2

FIG. 3

FIG. 4

pleted support. Other adjustable fastening means may be substituted.

It will be apparent that if a shirt be placed upon a coat hanger including such a collar support as that described, and the collar band buttoned, the collar will receive a formative support and will not be likely to be pulled out of shape and thus have its appearance spoiled.

If desired, the coat hanger and the collar support can be made integral as by forming the two of a plastic in a suitable mold or in any other suitable fashion.

I claim:

1. A blank adapted to be made up into a cylindrical shape for positioning on and attachment to a coat hanger having a cross-bar and a supporting hook, the blank comprising a strip of a flexible material generally of a rectangular shape and having a first set of cuts therein on the underside thereof and approximately midway of the length of the strip, said first set of cuts defining a tongue, said tongue having an aperture therein to fit over said hook, a second and a third set of cuts in the underside of said blank, each of said second and third cuts being located about midway between one of said first set of cuts and an end of said blank, said second and said third set of cuts each including an aperture portion adapted to fit snugly upon said hanger cross-bar, and means at the ends of said strip to secure the ends together.

2. A blank adapted to be made up into a cylindrical shape for positioning on and attachment

to a coat hanger having a cross-bar and a supporting hook, the blank comprising a strip generally of a rectangular shape and having a first set of cuts therein on the underside thereof and approximately midway of the length of the strip, said first set of cuts defining a tongue of generally trapezoidal outline, said tongue being folded upon itself to provide a plurality of folds fitting snugly together and having an aperture therein to fit over said hook; a second and a third set of cuts in the underside of said blank, each of said second and third cuts being located about midway between one of said first set of cuts and an end of said blank, said second and said third set of cuts each including an aperture portion adapted to fit snugly upon said hanger cross-bar, and means at the ends of said strip to secure the ends together.

FLORENCE G. DUGGAN.
